(57) **CLAIM**

The ornamental design for a bell curve shaped contoured soft sided temporary bathtub liner, as shown and described.

DESCRIPTION

FIG. 1 is a perspective view of the contoured bathtub liner embodying the design of the present invention.

FIG. 2 is a side elevational view thereof;

FIG. 3 is an end elevational view thereof;

FIG. 4 is an end elevational view thereof;

FIG. 5 is a top plan view thereof; and,

FIG. 6 is a perspective view of the bathtub liner in an unassembled, uninstalled position displaying one version of the three dimensional bell curve shaped contours in its two dimensional plane thereof.
